UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLER.

Application filed June 29, 1926. Serial No. 119,393.

My invention relates to the construction of car couplers and more especially to those of the type commonly known as locomotive and tender couplers, wherein the coupler shank is comparatively short and is pivotally connected to a pocket casting or bracket member.

The principal object of the invention is to provide a car coupler of the type indicated which is efficient in service and well adapted to resist the stresses and wear it is required to withstand.

The principal feature of the invention consists in pivotally connecting a car coupler to a pocket casting through the instrumentality of a pivot pin which is encircled by a sectional bushing, the divisions of the bushing being substantially coincident with the planes of the shearing forces to which the pivot pin is subjected.

A further feature consists in forming the coupler pocket with a plurality of pivot lugs disposed in spaced relation and in fashioning the car coupler with spaced pivot lugs which mesh therewith, each of the lugs being provided with a bushing for receiving a pin pivotally connecting the pocket member and coupler, and the alternate bushings being elongated so as to prevent the pin from being subject to buffing stresses.

Other features of the invention pertaining to advantageous forms and combinations of parts will hereinafter appear.

In the drawings illustrating the invention,

Figure 1 is a plan view of a car coupler embodying a preferred form of the construction.

Figure 2 is a view, partly in elevation and partly in vertical section, of the device shown in Fig. 1, a portion of the coupler head being omitted.

Figure 3 is a detail plan view showing one of the bushings in assembled relation to the part with which it is associated.

Figure 4 is a view corresponding to Fig. 3 but illustrating one of the elongated bushings.

Figure 5 is a detail view in side elevation showing the form of bushing preferably employed at the upper end of the pivot pin.

Figures 6 and 7 are views corresponding

to Fig. 2 but respectively illustrating modified forms of the invention.

In the drawings, 1 indicates a bracket member or coupler pocket which is adapted to be secured to the locomotive, tender or other vehicle to which it is to be applied. The coupler pocket is formed with a plurality of pivot lugs 2, 3 and 4, respectively, the latter being extended forwardly to provide a floor or shelf 5 for supporting the coupler 6 against sagging or drooping. These pivot lugs are integrally connected at the sides by the forwardly diverging lateral walls of the pocket member 1, as indicated at 7 and 8, the webs or walls 7 and 8 being flared with respect to each other so as to permit the coupler to have the desired range of swinging movement.

Positioned in the apertures of the pivot lugs 2, 3 and 4 are corresponding bushings 9, 10 and 11, respectively, through which the pivot pin 12 extends. The openings through each of these bushings is elongated in the direction of length of the coupler, as shown in Fig. 4, so as to prevent buffing stresses from being communicated to the pin 12. To prevent the bushings from turning with respect to the pivot lugs of the coupler pocket, each is preferably shouldered at its upper end to provide a rectangular collar 13 which fits in a corresponding recess in the adjacent pivot lug. In addition to being provided with the collar 13, the uppermost bushing 9 is preferably formed on opposite sides with upstanding lugs or flanges 14 which, by engaging correspondingly flattened faces 15 on the head of the pivot pin 12, prevent the latter from rotating in the bushings carried by the coupler pocket 1.

At its rear end the shank of the coupler 6 is bifurcated to provide spaced pivot lugs 16 which receive the intermediate pivot lug 3 of the pocket member between them. The rear end faces 17 of the pivot lugs 16 are curved cylindrically to cooperate with the correspondingly curved cylindrical surfaces 18 of the coupler pocket, thereby efficiently providing for the transmission of buffing forces to the latter in all angular positions the coupler 6 may assume. As shown in Fig. 2, the elongated bushings 9, 10 and 11 of the pocket member afford clearances for the

pivot pin 12 when the curved faces 17 and 18 are in contact, thereby relieving said pin of buffing stresses. The aperture in each of the pivot lugs 16 of the coupler is preferably provided with a bushing 19 having a cylindrical opening for the pivot pin. To prevent rotation of these bushings each may advantageously be shouldered at its upper end by fashioning it with a square flange 10 or collar 20 which fits into a corresponding recess formed in the neighboring surface of the corresponding pivot lug 16. The spaces in the coupler pocket into which the pivot lugs 16 of the coupler extend are of greater 15 height vertically than is the intermediate pivot lug 3, thereby permitting a shouldered bushing to be associated with said intermediate lug.

The modified form of the invention shown 20 in Fig. 6 is substantially the same as the construction heretofore described except that the holes in the bushings 21, 22 and 23 of the coupler pocket 24 are cylindrical instead of elongated, whereas the holes in the bushings 25 25 of the coupler 26 are elongated instead of cylindrical. By this alternative construction the pivot pin is relieved of buffing stresses as in the case of the construction heretofore described.

In the device shown in Fig. 7 the apertures 30 in the bushings 27, 28 and 29, respectively, carried by the pivot lugs of the pocket member 30 are cylindrical, and the apertures through the bushings 31 carried by the pivot lugs of the coupler 32 are also cylindrical. Other features of the invention embodied 35 in this form of construction correspond to similar features heretofore described and accordingly are indicated by corresponding 40 reference numerals.

I claim:—

1. In a device of the character indicated, the combination with a coupler pocket having a plurality of pivot lugs disposed with 45 relation to each other so as to provide a plurality of intervening spaces for receiving

corresponding portions of the shank of a car coupler, of a car coupler having spaced pivot lugs meshing with said lugs of the coupler pocket, bushings respectively associated with 50 said pivot lugs, said bushings and lugs having shouldered engagement, and a pin extending through said lugs and bushings for pivotally connecting the coupler pocket and car coupler, said spaces between the lugs of 55 the coupler pocket being of greater height than the vertical thickness of the pivot lug intervening between said spaces.

2. In a device of the character indicated, the combination with a coupler pocket having a plurality of apertured lugs disposed in spaced relation, of a car coupler provided with a plurality of apertured lugs meshing with said lugs of the coupler pocket, bushings respectively positioned in the apertures 60 of said lugs, and a pivot pin extending through said lugs and bushings for pivotally connecting the coupler pocket and car coupler, certain of said bushings being elongated so as to permit the coupler to engage 70 the coupler pocket and relieve the pivot pin of buffing stress.

3. In a device of the character indicated, the combination with a coupler pocket having a plurality of pivot lugs disposed in 75 spaced relation, of a car coupler having spaced pivot lugs meshing with said lugs of the coupler pocket, each of said lugs being provided with a bushing for receiving a pivot pin and being formed at one end with a 80 shouldered portion cooperating with a correspondingly shouldered part of the lug with which it is associated, and a pivot pin extending through said lugs and bushings for pivotally connecting the coupler pocket and car coupler, alternate bushings being elongated so as to permit the coupler to move 85 into engagement with the coupler pocket and relieve said pin of buffing stress.

In testimony whereof I affix my signature,

ENOCH GEORGE, JR.
